United States Patent Office

Des. 177,477
Patented Apr. 17, 1956

177,477

AIR CONDITIONER CABINET

Joseph R. Mango, Midlothian, Ill., assignor to The Emerson Electric Manufacturing Company, St. Louis, Mo., a corporation of Missouri

Application March 18, 1955, Serial No. 35,111

Term of patent 14 years

(Cl. D62—4)

Fig. 1.

Fig. 2.

Fig. 3.

Figure 1 is a perspective view of the front, top and one end of an air conditioner cabinet embodying my new design;

Figure 2 is a front elevational view thereof; and

Figure 3 is an end elevational view looking toward the end not disclosed in Figure 1.

The rear of my air conditioner cabinet is closed as required by a non-ornamental utilitarian plate.

I claim:

The ornamental design for an air conditioner cabinet, substantially as shown and described.
